UNITED STATES PATENT OFFICE

2,423,131

SELECTOR SWITCH FOR TELECOMMUNICATION SYSTEMS

Frans Van Laethem, Antwerp, Belgium, assignor
to International Standard Electric Corporation,
New York, N. Y., a corporation of Delaware

Application February 12, 1943, Serial No. 475,686
In the Netherlands September 12, 1941

5 Claims. (Cl. 179—27.51)

1

This invention relates to shafts with grooves, which are angularly spaced at different axial positions and to means such as molds of making such shafts.

One example of an embodiment of the invention is the formation of a molded shaft having at least one spiral groove, such as a molded worm shaft.

Such worm shafts are used in automatic telephony and may be applied in selectors such as is disclosed in British Patent No. 522,198.

Shafts are known, which are provided with projections thereon, such as spiral ribs and means are known for making such shafts of molded material, by using a plurality of unitary molded sections.

However, such constructions, provided with projections or ribs, have various disadvantages. In the cases of endless spirals or worms, special precautions have to be taken at the crossing points of the spiral in order to prevent the guided member leaving its correct path. It may further be desirable to strengthen the construction by giving the spiral ribs heavier dimensions. In such a case, however, the interrupted length at the crossing points of the spiral becomes too large.

These disadvantages can be avoided by using shafts, made according to this invention, using grooves. At the crossing points of the spiral, the isolated guide projections, required in the case of shafts with spiral ribs to prevent the guided member leaving its correct path, can be omitted. The interruptions at the crossing points are also much shorter, securing a better guidance for the sliding member. Furthermore, it can be seen that grooved spirals are of much stronger construction than spiral ribs.

One feature of the invention is that the shaft comprises a plurality of unitary molded sections, which are assembled and positively held from rotation relative to each other, and are provided with grooves, which are at different cross-sections of each section angularly spaced relative to one another. Each section may comprise at least one-half of the pitch of a spiral, if the grooves are spirally arranged on the shaft.

The sections comprise intermediate sections, which all have the same form, and end sections of another form. Together these sections may in one embodiment provide a right and left handed endless spiral groove around the shaft. These sections have further a special form in this respect, that the divisional lines between the separate sections are along a line of the side wall

2

of the grooves. The molds required for making the sections, comprise two members, the parting lines of which follow, therefore, the line of the side wall of the grooves. In this way the molding problem becomes extremely simple.

One embodiment of the invention will be described by means of the drawing, showing a shaft with endless grooves by means of which an axially movable member can be given reciprocatory movement by continuous rotation of the shaft in one direction. Also further molding means are shown in the drawing for making such shafts.

Fig. 1 shows a plan view of the worm shaft with a central steel shaft;

Fig. 2 shows an elevation view of the shaft, but without the central part;

Fig. 3 shows an end view of the shaft of Fig. 2; Fig. 4 shows the plan view of an end section;

Fig. 5 shows a side view of an end section; Fig. 6 shows a plan view of a penultimate section;

Fig. 7 shows a side view of a penultimate section;

Fig. 8 shows a plan view of an intermediate section;

Fig. 9 shows a side view of an intermediate section;

Fig. 10 shows an end view of an intermediate section;

Fig. 11 shows, in section, the mold for forming a section according to Figs. 8, 9 and 10;

Figs. 12 and 13 show the upper part of the mold for forming a section of the worm shaft, as shown in Fig. 6;

Figs. 14 and 15 show the lower part of the mold, in which a section of the worm shaft, as shown in Figs. 6 and 7, is formed, while Figs. 16, 17 and 18 show the respective upper parts of the mold, which is used for making a section of the form shown in Figs. 4 and 5.

If it is required to mold a shaft in phenol condensation products or other suitable synthetic molding products, the shaft is divided into sections each incorporating one-half of the pitch of the grooved spiral 1 in Fig. 1. All intermediate sections 7 are then identical in form and are molded in the same mold. The end sections 8, however, are different, because the spiral groove is continuous at the extremities of the shaft.

Special mold members are, therefore, provided for the end sections which can be placed in the same mold. The method of mounting the sections to form a complete shaft is shown in Figs. 1 and 2. The left-hand shaft section 8 abuts against a collar 6 which springs into a groove of

3

the spindle 3. The sections may be held together by the pressure of the spring 4, which spring is provided between the right-hand extreme end and a collar 5, fixed in the same way as collar 6.

The application of the invention is, of course, not limited to the illustrated method of mounting, which is based on the principle of holding the shaft assembled by spring pressure. Any suitable other method may therefore also be applied, for instance, the hollow sections may be threaded on a spindle and be held in place by nuts, screwed on the spindle. Another construction may be that the hollow shaft sections are formed with cooperating ribs and slots to prevent relative rotation, and are positioned between hollow end members, which fit the end of a wire spoke, riveted, for instance, at one end and provided with thread and nut at the other end, securing together in this way the assembly.

To prevent in the embodiment, as shown, the shaft sections from relative rotation and to secure perfect lining up of these sections, they may be provided in their hollow interior portion with a rib 2 which cooperates with a longitudinal groove in the spindle 3.

The mold (Fig. 11) comprises a main part 9, the closure pieces 10 and 11, in which the upper and the lower mold members 12 and 13 are fixed as also part 14, in which the core 15 is mounted.

The guide pins 16 and 17 assure that all these mold parts be kept in their exact correct mutual positions. The dowel pins 18 and 19 serve for fixing the upper and lower mold members in their respective closing portions 10 and 11.

The upper mold member 12 is provided with a tapered channel 20 for the injection of the molding compound. For molding end sections (Figs. 6 and 7) the lower mold member 13 of Fig. 11 is replaced by the lower mold member as shown in Fig. 14 and 15. For molding the extreme end sections (Figs. 4 and 5) the upper mold member 12 of Fig. 7 is replaced by the upper member shown in Figs. 16 and 17 and the lower mold member 12 by the lower mold member shown in Fig. 18.

A similar mold may, of course, be provided for

4

shaft sections having a single spiral groove or two parallel spiral grooves, or those having intermittent grooves spirally placed on the shaft.

What is claimed is:

1. A shaft for selector switches and the like, comprising a plurality of unitary molded sections, means for holding said sections in longitudinal relation to one-another, and means for preventing relative rotation of said sections with respect to one-another, said shaft being provided with grooves, which are at different cross-sections of each section angularly spaced relative to one-another, whereby the grooves of each section co-operate with the grooves of an adjacent section so as to give substantially the effect of a continuously grooved shaft.

2. Shaft according to claim 1, in which the grooves are arranged so as together to form a spiral extending the length of the shaft.

3. Shaft according to claim 1, in which each section includes at least one-half of the pitch of a grooved spiral.

4. Shaft according to claim 1, in which the grooves in the intermediate sections form two spirals, one right-hand and one left-hand, while the grooves in the end sections extend so as to connect said two spirals, whereby an endless spiral is formed, so that continuous rotation of the shaft will afford reciprocating motion of a member riding in said spirals.

5. Shaft according to claim 1, in which the means for holding together the sections include spring means for exerting axial pressure upon said sections.
